The uniformly segmented broken lines shown in the drawings illustrate stitching and do not form part of the claimed design. The intermittent crosshatching shown on both the interior and exterior pockets is netting. The intermittent crosshatching on the roll-type fastener for the handles illustrates material texture. Both types of crosshatching are understood to extend fully across the surfaces on which they reside, forming part of the claimed design. The intermittent parallel lining shown on the straps illustrates material texture and forms part of the claimed design.
